United States Patent Office

Des. 186,057
Patented Sept. 1, 1959

186,057

REFRIGERATOR

Carl W. Sundberg, Bloomfield Hills, Mich., assignor to Whirlpool Corporation, a corporation of Delaware

Application February 26, 1958, Serial No. 49,802

Term of patent 14 years

(Cl. D67—3)

The dominant portions of the design are shown in solid lines.

I claim:

The ornamental design for a refrigerator, as shown and described.
